UNITED STATES PATENT OFFICE

2,267,226

GOLFER'S APPLIANCE

James Corbett White, Waynoka, Okla.

Application October 20, 1939, Serial No. 300,453

1 Claim. (Cl. 150—1.5)

This invention appertains to new and useful improvements in golfer's appliances, and more particularly to a bag in which not only golf clubs can be carried but other articles such as sweaters, shoes, golf balls, tees, etc.

Another important object of the invention is to provide a golfer's appliance which is more in the nature of a traveller's case which affords accommodations not only for the golf clubs but for golfer's apparel changes.

These and other objects and advantages of the invention will become apparent to the reader of the following specification.

In the drawings:

Figure 1 represents a side elevational view of the bag.

Figure 2 is a side elevational view of the structure looking at the opposite side from that shown in Figure 1.

Figure 3 is an end elevational view.

Figure 4 is an end elevational view looking at the opposite end from that shown in Figure 3.

Figure 5 is a longitudinal sectional view through the bag.

Figure 6 is a horizontal sectional view of a slightly modified form of club compartment closure.

Referring to the drawings, wherein like numerals designate like parts, it can be seen in the drawings that numeral 5 represents one side of the case while numeral 6 represents the other side of the case. (See Figures 1 and 2, respectively.)

On the side wall 5 are two cleat structures 7 and 8, each of these cleat structures being provided with an outstanding formation 9 having keyhole slots 10 therein for the reception of the shafts of golf clubs. It is preferable that one cleat, that is, as shown, the cleat 8, be disposed obliquely across the wall 5 to accommodate clubs from the longest shaft to those having the shortest shaft.

The bag is further divided by the horizontal partition 11 into an upper compartment and a lower compartment and a liner 12 is provided for the upper compartment. This upper compartment is to contain the golf clubs in inclement weather or when they are not in use. When the clubs are to be used, they are set out in the racks 7 and 8 where they can be conveniently selected and replaced when required for use on the course. The keyhole slots in cleat 7 are larger than those in cleat 8 for accommodation of the grips of clubs when the clubs are shoved forward to hold said clubs securely in the rack.

The line 12 has secured thereto at one end an outwardly bulgeable closure structure 13 to accommodate the heads of the golf clubs, this clo-

sure 13 being slit but capable of being closed by the multiple fastener 14. The wall at the other end of the upper compartment carries a pair of vertically disposed cylinders 15 having slots at the forward side portions thereof. These cylinders are for containing golf balls and each has a spring closure 16 at its upper end.

The lower compartment, defined by the partition 11, has the intermediate vertical partition 17 therein, dividing the lower compartment into a compartment for shoes and the like and a compartment for apparel such as jackets, sweaters, etc. Each compartment 18—19 has a closure and these closures are denoted by numerals 20 and 21. The outer side of the closure 21 carries a golf tee receptacle 22 having the spring closure 23.

As shown in Figures 1, 2 and 3, a suitable handle, preferably of elongated structure, is provided at the top of the bag and denoted by numeral 24.

A slightly modified form of the invention is shown in Figure 6 wherein instead of the closure 13, a cylindrical closure 13a of substantially rigid structure is employed, the same having a circumferential flange 25 at its inner end capable of engaging the adjacent end wall of the bag to prevent being entirely pulled out. This closure 13a is adapted to be extended to accommodate golf club heads and the same has the hinged door 26 at its outer end which can be closed when the golf clubs are properly in place. When the golf clubs are carried in the racks 7 and 8, this closure 13a can be pushed to a contracted position, that is, a position extending into the upper compartment of the bag.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

45 A golfer's appliance comprising a case, a golf club supporting rack at one side of the case, said rack comprising a pair of cleats each having longitudinally spaced keyhole-shaper club receiving notches therein, one of said cleats being disposed 50 transversely across the side of the case, the other cleat being disposed obliquely across the side of the case, with one end thereof closer to the corresponding end of the other cleat than the proximity of the remaining ends to accommodate the shafts of shorter golf clubs than can be accommodated by the more spaced end portions of the cleats.

JAMES CORBETT WHITE.
